UNITED STATES PATENT OFFICE

2,227,506

CIRCUIT BREAKER

Merrill G. Leonard, Sharon, Pa., assignor to Westinghouse Electric & Manufacturing Company, East Pittsburgh, Pa., a corporation of Pennsylvania

Application September 10, 1937, Serial No. 163,202

19 Claims. (Cl. 200—116)

The invention relates to electrical control devices in general, and more particularly, to circuit breakers for mounting in transformers to control moderate power distribution or feeder circuits.

5 An object of the invention is the provision of an improved circuit breaker which is simple and compact in construction, reliable in operation and which can be manufactured and serviced at a very low cost.

10 Another object of the invention is the provision of a circuit breaker embodying an improved and simplified operating mechanism which is manually operable to open and close the contacts of the breaker with a snap action and automatically operable to open the contacts with a snap action in response to predetermined conditions irrespective of the position of the operating handle.

15 Another object of the invention is the provision of a circuit breaker embodying an improved operating mechanism which is mounted in recesses provided in the base of the breaker and the parts of which are held in mounted position by a single overcenter actuating spring which actuates the contacts.

20 Another object of the invention is the provision of a multi-pole circuit breaker in which the contact means of the several poles are capable of being independently tripped without opening the contacts of the other poles, but which are simultaneously opened and closed by a common operating member, the common operating member being operable to reset the operating mechanism of any or all poles that have been tripped.

25 Another object of the invention is the provision of a circuit breaker of the above-mentioned type, any of the poles of which is readily convertible into a signal-controlling relay to indicate the existence of an abnormal condition.

30 The novel features that are considered characteristic of the invention are set forth in detail in the appended claims. The invention itself, however, both as to structure and operation, together with additional objects and advantages 35 thereof will best be understood from the following detailed description thereof when read in connection with the accompanying drawings, in which:

35 Figure 1 is a plan view partly in section, of the circuit breaker embodying the features of the invention;

40 Fig. 2 is a sectional view of the circuit breaker taken substantially on the line II—II of Fig. 1 and looking in the direction of the arrows, the

parts of the breaker being shown in closed circuit position;

45 Fig. 3 is a sectional view similar to Fig. 2 showing the position of the parts when the breaker is manually opened;

50 Fig. 4 is a sectional view similar to Fig. 2 showing the position of the parts of the breaker in the tripped open position following a tripping operation;

55 Fig. 5 is an end elevational view of the circuit breaker illustrating the two current-responsive trip elements, the cover being removed to show these elements;

60 Fig. 6 is a side elevational view of one of the current-responsive trip elements of the breaker;

65 Fig. 7 is a view of the current-responsive trip element shown in Fig. 6 taken at right angles thereto; and

70 Fig. 8 is a sectional view of the circuit breaker, similar to Fig. 4, showing one of the poles modified to function as an overload responsive signal controlling device.

75 Referring to the drawings, the circuit breaker illustrated is of the two-pole type and includes a suitably recessed base or casing 9 which is preferably of molded insulating material, and which serves to support and enclose the various parts of the circuit breaker. The two poles of the circuit breaker are substantially identical and hence a detailed description of only one pole 80 will be given, since it is believed that it will be sufficient for a proper understanding of the invention.

85 Each pole of the circuit breaker comprises, in general, a stationary contact 11, a cooperating movable contact 13 carried by a movable switch arm 15, actuating means indicated generally at 17 for moving the switch arm to open and closed position, and a trip device indicated generally at 19, which is operable in response to predetermined conditions to cause the actuating means to 90 open the contacts of the breaker.

95 The stationary contact 11 is secured to the inner angularly bent end of a terminal conducting strip 21 which is secured to an end wall of the casing by suitable rivet fastening means 23. The opposite end of the terminal conducting strip 21 is angularly bent and extends outside of the casing 9 to form a means for connecting the breaker in an external circuit.

100 The movable contact 13 is carried by the switch arm 15 which is U-shaped, as best shown in Fig. 1. The switch arm 15 is stamped from sheet metal and is bent to provide a pair of parallel spaced legs 25 and a bight portion 27. The

movable contact is secured to a projection 29 which is formed integral with one of the legs 25 of the switch arm and bent at right angles thereto. The bight portion 27 of the switch arm 5 is provided with an angularly bent extension 31 which has a pair of lugs 33 extending laterally from the sides thereof and formed integral therewith, the purpose of which will be herein-after described.

10 The actuating means for the movable contact 13 comprises, in general, a pivoted support 35 for the switch arm 15, a movable operating handle 37 and an overcenter spring 39 connecting the operating handle and the bight portion of the 15 switch arm 15.

The pivoted support 35 is stamped from sheet metal plate and formed to provide a pair of spaced parallel legs 41 which are bent angularly as indicated at 43 and joined by a bridge portion 20 45. The support member 35 is pivotally supported by means of a pivot pin 47, the ends of which are 25 removably seated in suitable bearing recesses 49 formed in the casing. The support member 35 is also provided with a pair of inwardly bent 30 projections 51 which serve as bearings for pivotally supporting the switch arm 15. The switch arm 15 is nested within the legs 41 of the support 35 and the upper ends of the legs 25 of the switch arm are notched as indicated at 53 for pivotally 35 engaging the bearing projections 51 of the pivoted support 35. It will thus be seen that the switch arm 15 is removably mounted in pivotal engagement with the bearing projections 51 of the pivoted support 35 and that the pivot support is likewise 40 removably mounted in pivotal engagement with the bearing recesses 49 provided in the casing 8, and these elements are adapted to be releasably retained in pivotally mounted position by means of the overcenter spring 39. When in 45 mounted position the switch arm 15 and support 35 form an articulated switch member.

The operating handle is likewise stamped from sheet metal plates and formed to provide a pair of outstanding parallel legs 55 which are perforated, as indicated at 57, to engage and receive a common operated member which will herein-after 50 be described. The operating handle 37 is provided at each end with a pair of lateral projections 59 which are adapted to slide on spaced parallel 55 arcuate surfaces 61 formed on the moulded casing. Suitable ribs 62 are provided on the casing adjacent the arcuate surfaces 61 for guiding the operating handle 37 and for preventing lateral displacement thereof. The handle 37 and the bight 60 portion of the switch arm 15 are perforated to receive the bent ends of the overcenter spring 39. The overcenter spring 39 is held in tension between the bight portion 27 of the switch arm 15 and the operating handle 37 and thus serves to 65 maintain the switch arm 15, the pivoted support 35 and the operating handle 37, in mounted position in the moulded casing, as shown in Fig. 2.

The spring 39 is disposed between the legs of the switch arm 15 and the pivoted support 35, and in 65 the closed circuit position of the switch the line of action of the spring 39 is so disposed relative to the pivot axis 47 of the support 35 that it tends to bias the support in a clockwise direction about its axis 47. The pivoted support 35 is normally 70 held in the position shown in Fig. 2 by means of the current-responsive trip device, the bridging portion 45 of the support 35 being provided with a latch projection 63 which normally engages a latch 65 carried by the trip device, as shown in 75 Fig. 2.

The downward movement of the operating handles 37 is limited by a pair of stops 66 (only one being shown) formed on the arcuate surfaces 61 which engage the upper lateral projections 59 of the handles 37 in the closed circuit positions 5 of the handles shown in Fig. 2, the upward movement of the operating handles being limited by the engagement of the lower lateral projections 59 of the handles with a pair of extending portions 67 formed on the legs 41 of the pivoted supports 35 which extend between the sides of the handles 37 and the spaced arcuate surfaces 61.

The extensions 67 of the pivoted support 35 and the lower lateral projections 59 of the handle 37 form a means for resetting the support 35 when 10 the handle is manually moved upward beyond its normal open position following a tripping operation, as will be herein-after described.

The trip device indicated generally at 18 comprises a U-shaped bimetallic trip element 69 which has its a bight portion 71 secured to a pivoted adjusting member 73 by means of a plurality of rivets 75. The lower ends of the legs of the bimetallic trip element 69 have an insulating block 77 secured thereto by means of rivets 79. The latch 65, which is angularly off-set, as shown in Fig. 2, is secured to the lower end of the block 77 by means of a rivet 81. Instead of a U-shaped bimetal as shown, a single leg bimetal may be 30 used. The pivoted adjusting member 73 is provided with a pair of ears 83 which are formed integral therewith and bent at right angles to the portion of the member 73 to which is secured the bimetallic trip element 69. The ears 83 are provided with openings for engaging a pivot pin 85 35 which is mounted in the casing 9. The adjusting member 73 is thus pivotally mounted in the casing and it will be seen that a small rotative movement of the pivoted adjusting member 73 about its pivot pin 85 will change the position of the 40 latch 65 with respect to the latch projection 63 provided on the pivoted support 35.

The adjusting member 73 is provided with an angularly off-set extension 87 by means of which the member 73 may be moved to adjusted position about its pivot axis 88.

The right-hand end of the extension 87 of the adjusting member 73 is notched to receive an adjusting screw 89 which passes through a transverse wall 91 formed in the casing 9. The screw 50 89 is held in mounted position on the transverse wall 91 by means of a nut 93. An internally threaded adjusting screw 95 is threaded on the end of the screw 89 and engages the notched end of the extension 87 of the adjusting member 73. 55 The screw 95 extends through an opening 97 provided therefor in the front wall 99 of the casing and has an indicating pointer 101 secured thereto.

A coil spring 103 encircles the bolt 89 and engages the notched end of the extension 87 of the adjusting member 73 at one end and the transverse wall 91 at its other end. The spring 103 serves to maintain the extension 87 of the adjusting arm 73 in engagement with the adjusting 65 screw 95, as is shown in Figs. 2, 3 and 4. The front wall 99 of the casing 9 is provided with a semi-circular rib 107 which increases the creepage breakdown strength between the two poles and which may serve as an index scale for the 70 indicating pointer 101. The mid-portion of the rib 107 is provided with an inward projection 109 which serves to limit rotation of the pointer 101 and adjusting screw 95 in either direction.

From the above description of the trip device, 75

it will be apparent that when the screw 95 is turned in a clockwise direction, as viewed in Fig. 1, it will move the adjusting member 73 in a clockwise direction about its pivot pin 85, as viewed in Figs. 2, 3 and 4, and the clockwise movement of this adjusting member 73 will decrease the amount of overlap between the latch 65 carried by the trip element 69 and the latch projection 63 formed on the pivoted support 35. This adjustment of the screw 95 and resulting decrease in the overlapping engagement between the latch 65 and the latch projection 63 will cause the breaker to be tripped in response to a lower magnitude overload. Conversely, when the screw 95 is turned in a counter-clockwise direction, as viewed in Fig. 1, the amount of overlap between the latch 65 and the latch projection 63 is increased, so that under these conditions, the breaker will be tripped in response to a higher magnitude overload.

As has been previously mentioned, the structures of the two poles of the circuit breaker are identical, and are insulated from one another by a centrally disposed partition 110 formed in the casing 9. The operating handles 37 of the two poles are connected for simultaneous movement together by a common operating member 111, of insulating material, the operating member 111 being connected to the two poles by means of a yoke 113, the opposite arms 115 of which extend through the openings 57 provided therefor in the operating handles 37.

A suitable cover 117 of molded insulating material is provided for enclosing and protecting the current responsive trip devices 19. The cover 117 is provided with a central partition 119 which aligns with the partition 110 formed in the casing 9 so as to completely isolate the two poles of the breaker from one another.

The circuit for each pole of the breaker is the same and extends from a terminal strip 121, the end of which extends outside of the casing, through a flexible shunt conductor 123 to one leg of the bimetallic trip element 69 through the trip element 69, and a flexible shunt conductor 125 to the switch arm 15, through the switch arm 15 to the movable contact 13 and stationary contact 11 to the terminal strip 21.

The operation of the circuit breaker is briefly as follows: With the circuit breaker in closed position, as shown in Fig. 2, let it be assumed that it is desired to manually open the contacts of the breaker. To manually open the breaker, the common operating member 111 is moved in an upward direction, as viewed in Fig. 2 to effect simultaneous upward movement of the two operating handles 37. The upward movement of the operating handles 37 moves the line of action of the over-center springs 39 across and above the pivot axes 53 of the switch arms 15.

As soon as the line of action of the over-center springs crosses above the pivot axes 53, a component of the force exerted by the springs moves the two switch arms from closed position, as shown in Fig. 2, to the open circuit position shown in Fig. 3. This movement of the switch arms takes place with a snap action. The movement of the switch arms to open circuit position is limited by the engagement of the projection 31 of the switch arms 15 with the transverse walls 91 formed in the casing, as shown in Fig. 3.

To manually close the circuit breaker, the common operating member 111 is moved downwardly as viewed in Fig. 3, to effect simultaneous downward movement of the two operating handles 37.

The downward movement of the operating handles 37 moves the line of action of the over-center springs 39 across and below the pivot axes 53 of the switch arms 15. As soon as the line of action of the over-center springs 39 crosses the pivot axes 53 of the switch arms 15, a component of the force exerted by the springs moves the switch arms 15 from open circuit position shown in Fig. 3 to the closed circuit position shown in Fig. 2 with a snap action. As has been previously mentioned, the downward movement of the operating handle is limited by the engagement of the lateral projections 59 of the handles with stop projections formed on the spaced arcuate guide surfaces 61. It will thus be seen that predetermined movements of the common operating member 111 effect simultaneous opening and closing of the contacts of the two poles of the circuit breaker; the contacts of the two poles are capable of being independently tripped, however, by the trip devices.

When an overload of predetermined magnitude and duration occurs in the circuit through either one of the poles of the circuit breaker, the breaker being in closed position as shown in Fig. 2, the bimetallic trip element 69 of that pole is heated a sufficient amount to deflect in a direction away from the actuating means. The deflection of the trip element 69 causes the latch 65 to disengage the latch projection 63 of the pivoted support member 35, thus releasing the support member. When the support member 35 is released the over-center spring 39 of the actuating means of that pole moves the pivoted support 35 in a clockwise direction about its pivot axis 47 from the position shown in Fig. 2 to the position shown in Fig. 4. During this movement, the legs 41 of the pivoted support 35 engage the lateral projections 33 of the switch member 15 and move that member to a tripped open position, as shown in Fig. 4, 40 with a snap action to effect opening of the contact means and interruption of the circuit. Due to the fact that the contact means of the two poles have individual trip-free actuating means, the tripping open of the contacts of one pole of 45 the breaker does not affect or change the position of the contacts of the other pole so that the contacts of the other or unaffected pole remain in closed position. When both poles are tripped, however, as described above in connection with 50 one pole, the connected operating handles 37 and of course the common operating member 111 are moved to an intermediate trip indicating position by the over-center springs 39 providing this movement is not restrained by the operating 55 mechanism, the movement of the handles 37 to their intermediate trip position being limited by the engagement of the lower lateral projections 59 of the handles 37 with the extensions 61 of the movable supports 35.

Before the contact means can be reclosed following a tripping operation in either pole, it is necessary to reset the pivoted support 35 of the tripped pole to its normally latched position. To reset the circuit breaker following a tripping operation, the common operating member 111 is moved in an upward direction beyond the normal open circuit position thereof. During this movement, the lower lateral projections 59 of the handle of the tripped pole which engage the extensions 61 of the pivoted support 35 move that support in a counter-clockwise direction about its pivot axis 47 to return the support to its normally latched position, as shown in Fig. 2. In order to return the pivoted support 35 to its latched posi- 75

tion the common operating member 111 must be moved upward beyond normal or manual open circuit position. After the pivoted support 35 has been returned to latched position, the breaker 5 may be manually reclosed in the manner previously described.

The structure of the circuit breaker is such that either of the poles thereof, or both of them, may be readily converted into a current-responsive 10 signal controlling device. The manner in which either pole of the circuit breaker may be converted into a signal controlling device is illustrated in Fig. 8 of the drawings. The shunt conductor 125 instead of being connected to the 15 switch arm 15, is connected directly to the outgoing terminal strip 21. The switch arm 15 is provided with an auxiliary contact 116 which is secured to the angular projection 31 of the switch arm. A cooperating stationary contact 118 is secured to the transverse wall 91 in a position to be engaged by the auxiliary movable contact 116 when the switch arm is moved by the actuating means to the tripped open position, as shown in Fig. 8. If desired, the contact 118 may be made 20 longer so that it will be engaged by the contact 116 in both the tripped and manual open position of the switch arm 15.

The circuit through the converted pole of the breaker extends directly through the corresponding current-responsive trip element 69, and the main contacts 11 and 13 are not used. Thus the converted pole of the breaker does not function to interrupt the main circuit through such pole. The other pole, however, if unconverted, functions 35 as a circuit breaker. The auxiliary contacts 116 and 118 may be connected in a suitable signal circuit which is adapted to be energized by the closure of these contacts when the switch arm 15 of the converted pole is tripped. The bimetallic trip element 69 of the signal controlling 40 pole may be adjusted by means of the screw 95 to trip the switch arm open at any desired predetermined overload. The signal circuit controlled by the contacts 116 and 118 may receive 45 electrical energy from the line and transformer to which the breaker is connected by providing a shunt conductor 126 for connecting the terminal strip 21 with the switch arm 15.

It will thus be seen that the invention provides 50 an improved circuit breaker which is simple and compact in construction, reliable in operation and which can be manufactured and serviced at a very low cost. The particular structure of the circuit breaker whereby the handles, switch arms and 55 the pivoted supports are removably mounted in the molded casing and releasably held in mounted position by means of the over-center spring which actuates the switch arms, provides a very desirable and inexpensive circuit breaker structure. 60 It will be noted that there is but a single bearing means for the actuating mechanism which consists of the bearing recesses 49 formed in the molded casing. This bearing means and the arcuate guide surfaces 61 for the operating handles 65 together with the feature of the over-center springs acting to hold the various parts of the actuating means in mounted position entirely eliminates the necessity of a separate frame for supporting the actuating means and thus materially 70 reduces the manufacturing cost of the circuit breaker. The structure of the actuating mechanism is such that the contacts of the breaker are opened and closed with a snap action and the actuating mechanism of either pole that is 75 tripped may be readily reset by simply moving

the common operating member to a position beyond the normal manual open position.

While the invention has been disclosed in accordance with the provisions of the patent statutes, it is to be understood that various changes 5 may be made in the structural details thereof without departing from the spirit of the invention. It is desired, therefore, that the appended claims be given the broadest reasonable construction in the light of the prior art. 10

I claim as my invention:

1. In a circuit breaker, a switch member movable to open and to closed circuit position, actuating means therefor comprising a movable operating member and an overcenter spring for 15 moving said switch member to open and to closed circuit position, a pivoted member releasable to cause automatic opening of said switch member independently of said operating member, and a pivoted bimetal trip element normally restraining 20 said releasable member, a casing of molded insulating material for the breaker having a molded guide surface for said operating member which constitutes the sole support for said operating member and along which said operating 25 member is movable, said casing having bearings molded therein for said pivoted releasable member and for said pivoted bimetal element.

2. In a circuit breaker, a switch member movable to open and to closed circuit position, actuating means therefor comprising a manually operable operating member and an overcenter spring connected to said operating member, for 30 moving the switch member alternately to open and to closed circuit position, and a pivoted trip 35 member movable to cause automatic opening of said switch member independently of said manual operating member but remaining stationary during normal movement of said operating member, a casing of molded insulating material for 40 said breaker, said casing having a molded pivot bearing for said trip member which directly engages and supports the pivot of said trip member and having a molded bearing for said manually operable operating member which directly 45 engages and constitutes the sole support for said operating member, said overcenter spring serving to maintain said operating member in mounted engagement with its molded bearing.

3. In a circuit breaker, a pivoted support, trip means releasably retaining the support in operative position, a switch member pivoted to said support and movable to open and to closed circuit position, a movable operating member, an overcenter spring connecting said operating 55 member to said switch member for moving the switch member to open and to closed circuit positions in response to predetermined movements of said operating member and for moving said support to an inoperative position when released to cause movement of the switch member to open circuit position, a casing provided with a bearing means for pivotally supporting the movable support, and also provided with an arcuate guide surface along which said operating 60 member is movable and which constitutes the sole support for the operating member, said guide surface having a slot for accommodating the connection of said spring to said handle.

4. In a circuit breaker, a pivoted support, trip 70 means releasably retaining the support in operative position, a switch member pivoted to said support and movable to open and to closed circuit position, a movable operating member, an overcenter spring connecting said operating mem- 75

ber to said switch member for moving the switch member to open and to closed circuit position in response to predetermined movements of said operating member and for moving said support to an inoperative position when released to cause movement of the switch member to open circuit position, a casing provided with a bearing means in which the pivoted support is removably pivoted, and also provided with spaced arcuate guide surfaces disposed in the same arcuate plane along which said operating member is movable, said guide surfaces constituting the sole support for the operating member, said spring being connected to said operating member through the space between the guide surfaces and serving to yieldingly maintain said support in engagement with the bearing means and the operating member in engagement with the guide surfaces.

5. In a circuit breaker, relatively movable contacts, actuated means therefor including a normally restrained biased member releasable in response to predetermined conditions to cause opening of said contacts, and an operating member movable to open and to closed position to cause said actuating means to open and to close said contacts, a casing for said contacts and actuating means provided with an elongated opening bounded on its two long sides by a pair of spaced parallel arcuate guide surfaces for supporting said operating member and along which said operating member is movable, said operating member having lateral projections for slidably engaging said guide surfaces, said releasable member having a portion which projects into the path of at least one of said projections between said operating member and one of said guide surfaces when said member is released to be engaged and moved by said projection for resetting said releasable member in response to a predetermined movement of said operating member.

6. In a circuit breaker, a recessed base, a stationary contact mounted on said base, a pivoted support having a removable pivotal engagement with bearing means provided in said base, a contact arm pivoted to said support, trip means for releasably retaining said support in operative position, an operating handle movable along a guide recess provided on the base, and an over-center spring connecting said handle to said contact arm for moving said arm into and out of engagement with the stationary contact in response to movement of said handle and for moving said support to an inoperative position when the support is released by the trip means for moving the contact arm to open position, said spring serving to maintain said support in engagement with its bearing means and said handle in engagement with the guide recess, and said guide recess constituting the sole support for said handle.

60 7. In a circuit breaker, a base having a recess, a stationary contact mounted in the recess, an articulated switch member having a support portion removably mounted in the recess in pivotal engagement with bearing means provided on the base, and a contact portion movable relative to the support portion, trip means for releasably retaining the support portion of the switch member in operative position, an operating handle movable along a guide surface provided on the base, and an over-center spring connecting the operating handle to the contact portion of the switch member for moving the contact portion to open and to closed position in response to movement of the handle and for moving the support portion to inoperative position to effect move-

ment of the contact portion to open position when the support portion is released by the trip means, said spring serving to maintain said switch member and handle in mounted position on the base, and said guide surface constituting the sole support for said handle.

8. In a circuit breaker, a base having a recess, a stationary contact disposed in the recess, a pivoted support removably mounted in pivotal engagement with bearing recesses formed in the side walls of the recess, a contact arm pivotally engaging said support, trip means for releasably retaining the support in operative position, an operating handle movable along a guide surface provided on said base, and an over-center spring connecting the handle to the contact arm for moving the contact arm to open and to closed circuit position in response to predetermined movements of the operating handle and for moving the support when released by the trip means to an inoperative position to effect movement of the contact arm to open position, said spring serving to maintain said support in engagement with its pivot bearing recesses, said handle in engagement with its guide and said contact arm in pivotal engagement with the support.

9. In a circuit breaker, a base of molded insulating material having bearings molded therein, a switch member movable to open and to closed position, actuating means for the switch member including a releasable support for the switch member movable to an inoperative position when released to cause opening movement of the switch member, means normally holding said support stationary, a movable operating handle and an over-center spring connecting the handle to the switch member for actuating the switch member in response to predetermined movements of the handle and for moving the support to its inoperative position when released, said support remaining stationary during manual operation of the breaker, said support and said handle being removably mounted in engagement with the bearings and held in mounted position by said spring.

10. In a multi-pole circuit breaker, a plurality of poles, each comprising a pivotally mounted support, trip means for releasably retaining the support in operative position, a contact member having a movable contact rigid therewith, said contact member being pivoted directly to the support and movable to open and to closed position, a movable operating handle, an over-center spring connecting the handle to the contact member for actuating the contact member in response to predetermined movements of the operating handle and for moving the support to an inoperative position when released by the trip means to cause movement of the contact member from one position to another position irrespective of the position of the operating handle, and a single movable operating member connected to the operating handles of the several poles for simultaneously operating all of the switch members.

11. In a multi-pole circuit breaker, a plurality of independently movable switch members one for each pole, a contact on each switch member, an individual actuating means for each switch member comprising a releasable support for the switch member movable from a normal latched position to an inoperative position to cause movement of the switch member from one position to another position, said switch member being in direct engagement with said support, a movable operating handle, an over-center spring connecting the handle to the switch member for moving the

- switch member between said positions in response to the movements of the handle and for moving the support to an inoperative position when the same is released, and a trip means operable to effect release of the support in response to predetermined conditions; a common operating member connected to the several operating handles movable between two positions for simultaneously operating the switch members between their two positions, each trip means being operable entirely independently of the other trip means and being free of any connection with the other trip means whereby operation of any one of the trip means causes movement of its corresponding switch member only, without changing the position of the other switch members, a single unitary base of molded insulating material on which the aforementioned parts of the breaker are mounted.
12. In a multi-pole circuit breaker, a plurality of independently movable switch members one for each pole, an individual actuating means for each switch member comprising a pivoted releasable support for the switch member movable from a normal latched position to an inoperative position to cause movement of the switch member from one position to another position, each switch member directly pivotally engaging its releasable support, a movable operating handle, an over-center spring connecting the handle to the switch member for moving the switch member between said positions in response to the movements of the handle and for moving the support to an inoperative position when the same is released, and a trip means operable to effect release of the support in response to predetermined conditions comprising a pivotally mounted bimetal trip element for each support; a common operating member connected to the several operating handles for simultaneously operating the switch members to their two positions, each trip means being operable entirely independently of the other trip means and being free of any connection with the other trip means whereby operation of any one of the trip means causes movement of its corresponding switch member only without changing the position of the other switch members, said operating handles having means for engaging and resetting the supports to their normal latched position in response to a predetermined movement of the operating member, and a single unitary base of molded insulating material on which the aforementioned parts of the circuit breaker are mounted, said base having bearings molded therein for said pivoted releasable supports and for said pivoted bimetal elements.
13. In a circuit controlling device, a movable switch member, a support for the switch member that is movable from a normal position to a tripped position for moving said switch member to a tripped position, said switch member being mounted in pivotal engagement with said support, trip means for normally retaining said support in its normal position and operable in response to predetermined conditions to release said support, a movable operating handle, an over-center spring connecting said handle to said switch member for moving said switch member in response to predetermined movements of said handle and for moving said support to its tripped position when the same is released, a stationary contact engaged by said switch member only when the switch member is in its tripped position.
14. In a circuit controlling device, a movable

switch member, a support for the switch member that is movable from a normal position to a tripped position to cause movement of the switch member to a tripped position, said switch member being mounted in pivotal engagement with said support, trip means for normally restraining said support in its normal position and operable to release the same in response to predetermined conditions, actuating means for moving the switch member independently of the support, and for moving the support from its normal to its tripped position when the support is released, and for resetting said support to its normal position, and a contact disposed to be engaged by said switch member only when the switch member is in its tripped position.

15. In a circuit breaker, a base of molded insulating material having a bearing molded therein of the same material as the base, a support pivoted in said bearing directly on the insulating material of said base, a movable contact arm, trip means for releasably retaining said support in a predetermined position, an operating handle movably supported directly on the insulating material of the base for moving the contact arm to open and to closed circuit position, said support when released by said trip means causing movement of said contact arm to an open circuit position.

16. In a circuit breaker, a base of molded insulating material having a bearing molded therein of the material of the base, a support removably pivoted in said bearing directly on the insulating material of said base, trip means for releasably retaining said support in a predetermined position, a movable contact arm, an operating handle removably supported directly on the insulating material of said base, an over-center spring for moving said contact arm to open and to closed circuit position in response to movement of said handle to open and to closed position, and for moving said support when released by said trip means to cause movement of said contact arm to an open circuit position.

17. In a circuit breaker, a base of molded insulating material having a bearing molded therein of the material of the base, a pivoted support removably mounted in pivotal engagement with said bearing directly on the insulating material of said base, a contact arm pivoted to the support, trip means for releasably restraining said support in operative position, an operating handle movable along a guide surface on said base of the material of the base, an over-center spring connecting said handle to said contact arm for moving said arm to open and to closed circuit position in response to predetermined movement of said handle and for moving said support to a tripped position when the support is released by the trip means to cause movement of the contact arm to an open circuit position, said spring maintaining said support in engagement with its bearing and said handle in engagement with said guide surface.

18. In a circuit breaker, a casing of molded insulating material, relatively movable contact means in said casing, actuating means for said contact means comprising a movable operating handle and an overcenter spring connected to said handle for manually actuating said contact means, and a pivoted member releasable in response to predetermined conditions to cause automatic opening of said contact means irrespective of the position of said handle, said releasable support normally being held stationary

and remaining stationary during manual operation of the breaker, said casing having a molded bearing surface for said operating handle which directly engages and constitutes the sole support 5 for said handle and having a molded pivot bearing which directly engages and supports the pivot of said releasable member.

19. In a circuit breaker, a casing of molded insulating material molded to provide a chamber, 10 a stationary contact in said casing, an arcuate bearing groove at one end of said casing having a central elongated opening therein joining said chamber, a pair of blind recesses in the sides of said casing extending inwardly from the opposite end of said casing along the sides of said chamber toward the arcuate bearing groove, the blind ends of said recesses forming bearings, a stationary contact mounted in said chamber, a yoke shaped carrier lever pivoted on a pivot pin

supported in the bearings formed by said blind recesses, a yoke shaped contact carrying member disposed between the sides of said carrier lever and pivoted to said carrier lever, a contact on said contact carrying member for engaging said stationary contact, an operating handle bearing against said arcuate bearing surface and movable back and forth along said surface, an overcenter spring connecting said contact carrying member and said operating handle, said spring being disposed between the sides of said contact carrying member and having a connection with said handle through said elongated opening in said arcuate guide surface, and a thermally controlled latch for normally 15 engaging and restraining said carrier in an operative position. 5

MERRILL G. LEONARD.
